UNITED STATES PATENT OFFICE.

THOMAS J. FLAGG, OF NEW YORK, N. Y.

DESIGN FOR A MADE-UP SCARF.

SPECIFICATION forming part of Design No. 15,141, dated July 15, 1884.

Application filed May 3, 1884. Term of patent 7 years.

To all whom it may concern:

Be it known that I, THOMAS J. FLAGG, of the city, county, and State of New York, have invented a new and original Design for a Made-up Scarf; and I do hereby declare that the following is a full and exact description thereof, reference being had to the accompanying drawing, and to the letters of reference marked thereon, making a part of this specification.

My design involves the configuration of the outer apron, S, of the scarf as its prominent feature; and it consists, as represented in the drawing, of the two counterpart inwardly-curved side lines, B C and B' C', and of the two unequal inwardly-inclined curved top lines, B A and B' A, which, starting from the points B and B', intersect to form an upper angle, A, upon one side of an imaginary central line, y y, running longitudinally midway between the two side lines, B C and B' C'. The lower ends of these two equal side lines are connected by two inwardly-curved lines, C D and C' D, intersecting to form an angle, D, on the imaginary central line, y y; but the form of the lower end of the scarf between the points C and C' is not an essential feature of the design, and may therefore be varied to include either a straight line or a curved line between said two points C C', instead of the broken line C D C. The design is completed by the upper line, A A', extending parallel

with an imaginary line drawn through the points or angles B B' far enough to be bisected by the imaginary central line, y y, and which, in connection with the outer inwardly-curved line, A' B, which is a counterpart of the line A B', and with a line extending from the angle A' to the point E on the line A B, at which said line is intersected by the imaginary central line, y y, serves not only to complete the outline of the entire scarf, but also of its inner apron, T, and center piece, U.

I claim—

The design for a made-up scarf, herein shown and described, which consists of the two counterpart inwardly-curved side lines, B C and B' C', in combination and connection with the two unequal inwardly-inclined curved top lines, B A and B' A, intersecting at A, and which, with a line, either broken, curved, or straight, connecting the points C C', define the outline of the outer apron, S, of the scarf, and with the upper lines, A A', A' B, and A' E, which define the inner apron, T, and the center piece, U, and complete the configuration of the entire scarf.

In testimony whereof I have signed my name to this specification in the presence of two subscribing witnesses.

THOMAS J. FLAGG.
